UNITED STATES PATENT OFFICE.

BASILE DESROCHERS, OF BEAUCEVILLE, QUEBEC, CANADA.

RAIL-JOINT.

1,359,238.

Specification of Letters Patent. Patented Nov. 16, 1920.

Application filed February 27, 1920. Serial No. 361,679.

To all whom it may concern:

Be it known that I, BASILE DESROCHERS, a citizen of Canada, residing at Beaucheville, in the Province of Quebec and Dominion of Canada, have invented new and useful Improvements in Rail-Joints, of which the following is a specification.

The present invention has reference to means for connecting the meeting ends of railway rails.

The object of the invention is to produce a rail joint in which the rail ends will be held in alinement under all conditions so that the wheels of the rolling stock will be afforded a free passage thereover without danger of contacting the ends of the rails when the latter are spread away from each other by the contraction thereof.

Other objects and advantages will present themselves as the nature of the invention is better understood, reference being had to the accompanying drawings in which there is illustrated a simple and satisfactory embodiment of the improvement reduced to practice.

In the drawings:—

Figure 1 is a side elevation of two rails constructed and connected in accordance with this invention.

Fig. 2 is a similar view but looking toward the opposite side of the joint.

Fig. 3 is a top plan view thereof.

Fig. 4 is a transverse sectional view approximately on the line 4—4 of Fig. 3.

Fig. 5 is a similar sectional view approximately on the line 5—5 of Fig. 3.

Fig. 6 is a horizontal sectional view approximately on the line 6—6 of Fig. 1.

Fig. 7 is a perspective view of one of the rail ends.

Fig. 8 is a perspective view of one of the joint plates.

Fig. 9 is a similar view of a second joint plate.

The rails 10—10 have their body portions of the usual construction, and the said rails, at a distance from their ends have their head portions 11 cut away in a line with the sides of the webs 12. Thus the heads

11 terminate in shoulders 13. The webs 12 at the ends of the rails are notched, providing inner straight shoulders 14.

The joint plate for the outside of the rails is broadly indicated by the numeral 15. This plate includes a channeled base 16, the channeled portion of the said base being

of a size and shape to snugly receive therein in the base flanges 17 on the outer sides of the rails 10. The base 16 of the joint plate 15 has on its inner edge an upstanding flange 18. This flange is of an equal thickness throughout, except that the same, on its inner face and at its center is formed with a widened inwardly projecting substantially rectangular tongue 19. The flange 18, at the corners thereof is notched as indicated by the numeral 20, and the inner walls 21 of the notches are vertical. The flange 18 is of a thickness greater than the distance between the sides of the webs 12 and the outer sides of the heads 11 of the rails 10, the tongue 19 is of a length equal to that of the notched upper corners of the webs 12, the ends of the said tongue being designed to contact with the shoulders 14 provided by the said notched webs, and the walls or shoulders 21 provided by the notched corners of the joint plate 15 are designed to contact with the shoulders 13 provided at the ends of the rail heads 11. The inner joint plate is broadly indicated by the numeral 22. This joint plate also includes a channeled base 23 which is designed to receive therein the inner portions of the base flanges of the rails. On the inner edge of the base 23 there is a thickened vertically projected flange 24 which is centrally formed, on its inner edge with a reduced upstanding tongue 25. The under faces of the heads of the rails are designed to rest on the upper edge of the flange 24, which is also true with respect to the upper walls provided by the notches at the corners of the joint plate 15. The tongue 25 is of a thickness equal to the distance between the sides of the webs and the outer faces of the heads of the rails. In this connection it should be stated that the tongue 19 is of a thickness equaling that of the webs of the rails. The length of the tongue 25 equals the distance between the shoulders 13 provided by the ends of the heads 11 of the rails, when the said rails are brought together, and the ends of the tongue 25 contact with said shoulders.

Passing transversely through the joint plates 15 and 22 as well as through suitable openings in the webs of the rails 10 are securing elements in the nature of bolts 26. These bolts are engaged by nuts 27, and as the said nuts may rest on the upper face of the base flange of either of the joint plates,

directly outward of the vertical flange thereof, accidental turning of the nuts will thus be prevented. However, if desired, the bolt opening in one of the joint plates may have 5 its outer portion squared to receive the squared shoulder at the headed portion of the bolts, in which instance the nuts cannot contact with the base flanges and be so held, but suitable means may be provided 10 for holding the nuts against turning.

With my improved rail joint it will be seen that no gaps can take place between the meeting ends of the joint plates and the rails into which the wheels of the rolling stock 15 might fall. The widened flange 18 of the joint plate 15 insures a free travel of the wheels over the confronting ends of the rails. The construction is simple but very 20 strong and effective and the rails will be positively held against tilting or vertical movement, while at the same time a limited longitudinal movement, incident to expansion and contraction is afforded.

Having thus described the invention, what 25 I claim is:—

1. In a rail joint two abutting rails each having the sides of its head cut away in a line with the sides of its web at a point adjacent its ends and its web notched at its 30 outer corner, inner and outer joint plates, each having a channeled base to receive the foot portion of the rails and an upstanding flange on the inner edge of the base, one of 35 said flanges being notched at its corners to receive thereon the under faces of the rail heads and the portion of the flange between the notches being arranged between the ends of the rail heads, said last mentioned portion having a tongue received in the notched

rail webs, the upstanding flange of the second plate receiving thereon the under faces of the rail heads on the second side of the rails and having a central reduced upstanding tongue filling the gap between the rail heads on said side of the rails, and connecting means between the plates and rails. 40

2. In a rail joint two abutting rails each having the sides of its head cut away in a line with the sides of its web at a point adjacent its ends and its web notched at its 45 outer corner, inner and outer joint plates, each having a channeled base to receive the foot portion of the rails and an upstanding flange on the inner edge of the base, the flange of the outer plate being of a greater 50 thickness than the distance between the webs and the outer faces of the heads of the rails, and being notched at its corners to receive thereon the under faces of the heads of the rails, and the portion of the flange between 55 the notches being arranged between the ends of the rail heads, a tongue formed on the last mentioned portion received in the notched rail webs, the upstanding flange on the second joint plate receiving thereon the 60 under faces of the rail heads on the second side of the rails, and having a central upstanding tongue at its inner edge of a thickness corresponding to the distance between the webs and the outer faces of the rail 65 heads and of a length filling the distance between the terminals of the adjacent rail heads, said tongue filling the gap between the rail heads, and connecting means between the plates and rails. 70

75 In testimony whereof I affix my signature.

BASILE DESROCHERS.
